Howard C. Thompson
ATTORNEY

UNITED STATES PATENT OFFICE.

LAWRENCE A. KIANDER, OF NEW YORK, N. Y.; ANNA MATHILDA KIANDER EXECUTRIX OF SAID LAWRENCE A. KIANDER, DECEASED.

BRIDGE WORK.

Application filed June 8, 1925. Serial No. 35,522.

This invention relates to the art of dental surgery and particularly to artificial dentures or bridge work; and the object of the invention is to provide an improved bridge work for one or more artificial teeth which is of such structure as to rigidly and securely support the artificial tooth or teeth in position in such manner as to expose the least amount of metal of the bridge work externally of the teeth or the exposed areas thereof whereby the present objections to crowns and like constructions are obviated; a further object being to provide a bridge construction which by reason of the method of its assemblage in connection with the sound and permanent teeth will obviate the necessity of grinding off the surfaces of sound or healthy teeth to facilitate the attachment of the bridge thereto in accordance with the present methods and especially when such sound teeth are disposed angularly with reference to a vertical or perpendicular plane extending through the jaw in which said teeth are mounted, in which instances it is customary with the present method of dental surgery to grind off large areas of the teeth and many times grinding to the sensitive structure of the tooth, resulting in time, in the decay or infection of such ground teeth; a further object being to provide a bridge construction, the securing or mounting means of which is such as to firmly and securely engage the teeth in connection with which the same is mounted; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is an outside face view of a part of a jaw indicating two natural teeth between which are two artificial teeth mounted in connection with and supported by said first named teeth.

Fig. 2 is a section on the line 2—2 of Fig. 1.

Fig. 3 shows sectional detail views of a number of parts of the device in superimposed relation, the section of one of the parts being on the line 3—3 of Fig. 4 of the drawing.

Fig. 4 is a plan view of one of the parts shown in Fig. 3; and,

Fig. 5 is a plan view of another of said parts.

It will be understood that my invention is adapted for the purpose of mounting one, two or more artificial teeth in connection with two natural teeth and for the purpose of illustrating one use of my invention, or method of carrying my invention into effect, I have shown in Figs. 1 and 2 of the accompanying drawing, a bridge construction comprising two artificial tooth structures 10 and 11, each of which are substantially of the same construction but being of different form to represent the natural arrangement of teeth, or to reproduce the teeth removed from a given jaw, and comprise metal backings 10^a and 11^a composed of any suitable or desirable metal such for an example, gold, said members 10^a and 11^a having substantially flat outer faces provided thereon with projecting pins 12 of cylindrical form, adapted to engage sockets in the porcelain or other artificial tooth representation facings, one of which only is shown mounted in position, namely the face 10^b. It will be noted when these facings are mounted in position, the metal backings 10^a and 11^a are not visible when viewed from the front of the teeth, the upper ends of said backings extending to the top portion of the teeth to give strength and durability thereto.

The backings 10^a and 11^a of the artificial tooth structure may be made integral or may be separately formed and soldered or otherwise joined together as at 13, and in practice I mount in the backings 10^a and 11^a, box-shaped socket members 14 which are preferably arranged adjacent one side portion of the backings 10^a and 11^a as illustrated in the drawing and the outer faces or edges of which are countersunk in said backings and

lie flushly with the substantially flat outer faces of said backings. The members 14 or one of them is shown in detail in Figs. 3 and 4 of the drawing, said members being each provided in the outer face thereof with a dove-tailed socket 15 opening out through one side edge as seen at 16 and centrally of said member is an inwardly directed tubular member 17 internally threaded as seen at 18 to receive a screw or other threaded member 19 as seen in Figs. 2 and 3 of the drawing. The inner end of the tubular member 17 may be closed if desired. The members 14 are so arranged on the backings 10^a and 11^a as to direct the opening 16 of the dove-tailed socket 15 out through one side edge of each of said backings or the outer edges thereof, when said backings are coupled together as seen in the drawing.

20 I also provide an attaching plate 20, one end of which is dove-tailed to fit snugly within the socket 15 and provided with a countersunk aperture 21 to receive the head of the screw 19 and the other end of said plate is extended angularly with reference to the first named end and the free edge of which is tapered as seen at 22.

25 I also provide in the construction shown, two tooth band members 23 and 24 which are fashioned from thin metal to conform with and fit snugly upon the rear faces of two natural teeth 25 and 26 respectively in such manner that the back portions thereof are not visible when viewing the teeth 25 and 26 from the front and each of said members 23 and 24 are provided with band portions 23^a and 24^a formed integrally therewith and which extend forwardly around the front of the base portion of the teeth 25 and 26 adjacent the roots of said teeth and the free ends of said band portions 23^a and 24^a are tapered or beveled slightly and adapted to be secured to the plates 20 as seen at 27 in Fig. 2 of the drawing and indicated in Fig. 3 of the drawing, this construction and operation making the separate plates 20 integral with the band portions 23^a and 24^a as will be apparent.

30 It will be understood that the band members 23 and 24 may be formed integrally with the backings 10^a and 11^a when said backings are integrally formed or the backing 10^a and member 23 may be integrally formed and the backing 11^a and member 24 integrally formed and these parts secured together as at 13 or all of the parts 10^a and 11^a, 23 and 24 may be independently formed and secured together. In mounting the artificial teeth in position by my improved bridge construction, and after said artificial teeth including the backings and facings thereof have been formed and the members 14 mounted in the backings 10^a and 11^a or secured therein in the formation of said backings, and after the band members 23

and 24 have been formed and properly fitted in accordance with the dental surgical art and especially after the band portions 23^a and 24^a have been fitted and formed around the natural teeth 25 and 26, the free ends of said bands are secured to the plates 20 as at 27 by soldering or in any other manner, and in such a way as to properly line the dove-tailed end portion of the plates 20 with the dove-tailed sockets 15 of the members 14 75 whereby the passing of the screws 19 through the apertures 21 of the plates 20 and into the threaded apertures 18 of the sleeve 17 will bring the outer faces of the plates 20 flush with the outer faces of the backings 10^a and 11^a, it being preferred that a slight clearance be allowed between the plates 20 and the outer faces of the sockets 15 of the members 14 to permit inward movement of the plates 20 to place the band portions 23^a and 24^a under slight tension to firmly and rigidly engage the teeth 25 and 26. The clearance referred to is indicated at 28 in Fig. 2 of the drawing. It will be understood that after the band members 23 and 24 have been mounted in position to properly support the backings of the artificial teeth between the natural teeth 25 and 26, the facings of the artificial tooth structure are mounted and secured in position in the usual manner by a suitable cement used for this purpose, and when the entire bridge work has been completed, the only thing visible externally of the teeth or the teeth as viewed from the front will be the band portions 23^a and 24^a, 100 all of the other metal structure being at the back of the teeth, thus producing a very desirable appearance, especially as compared with the appearance of caps and other bridge mountings of this class, as in common use.

105 As hereinbefore set out, one of the principal objects of the invention is to avoid the necessity of grinding healthy teeth to permit of the mounting of bridge work and other artificial surgery in connection therewith, especially in grinding off the adjacent side portions of teeth arranged at an inclined plane with reference to a vertical plane through the teeth and jaw structure. It may be necessary however, with my improved construction, as in other constructions to grind away a part of the teeth or that part of the teeth on which the band members are mounted to compensate for the bite, but aside from this operation, no other grinding of the teeth is necessary.

110 It will be apparent that the tooth facings employed and mounted upon the backings 10^a and 11^a serve when secured in position by cementing or otherwise to retain the plates 20 and screws 19 against accidental displacement and also to conceal such mountings, while the dove-tail form of the plates 20 and the dove-tail socket 15 retain the band 115 120 125 130

portions 23^a and 24^a against lateral displacement, the dove-tail structure acting as an anchoring means as will be apparent. This construction produces a strong and durable structure, it being understood that the screws 19 merely serve to move the plates 20 and the band portions 23^a and 24^a into proper position.

It will also be apparent that my invention is not necessarily limited to the specific shape and form of the parts 14 and 15 herein shown and described, nor to the method of their mounting in connection with one or more of the backings for artificial teeth, nor am I necessarily limited to the details of construction herein shown and described, the arrangement thereof or the method of mounting and assembling the same, and other changes in and modifications of the construction herein shown and described, may be made within the scope of the appended claims without departing from the spirit of my invention or sacrificing its advantages.

25 Having fully described my invention, what I claim as new and desire to secure by Letters Patent, is:—

1. A bridge construction comprising an artificial tooth structure, tooth engaging means at the opposite sides of said artificial tooth structure and integral therewith, said means involving adjustable clamping bands for fixedly securing and supporting the artificial tooth structure in connection with teeth disposed at the opposite sides thereof, said artificial tooth structure including a backing member, and means mounted in and constituting part of said member for retaining the clamping bands in connection therewith.

2. A bridge construction comprising an artificial tooth structure, tooth engaging means at the opposite sides of said artificial tooth structure and integral therewith, said means involving adjustable clamping bands for fixedly securing and supporting the artificial tooth structure in connection with teeth disposed at the opposite sides thereof, said artificial tooth structure including a backing member, means mounted in and constituting part of said member for retaining the clamping bands in connection therewith, and an artificial tooth facing secured to said backing and concealing said last named means.

3. A bridge construction comprising an artificial tooth structure, band members disposed at the opposite sides of said structure and integral therewith and including band portions adapted to encircle teeth disposed at the opposite sides of the artificial tooth structure, said artificial tooth structure comprising backing and facing members, and means for securing the free ends of the band portions to said backing comprising means

secured to the ends of said band portions and mounted in said backing.

4. The herein described means for mounting an artificial tooth structure comprising a socket member mounted in said tooth structure, and a clamp band member including a tooth encircling band portion and a part adapted to be mounted in connection with the free end of said band portion to engage said socket member.

5. The herein described means for mounting an artificial tooth structure comprising a socket member mounted in said tooth structure, a clamp band member including a tooth encircling band portion, a part adapted to be mounted in connection with the free end of said band portion to engage said socket member, means for retaining said part in said socket member, and said part and socket member being fashioned to prevent lateral displacement thereof one upon the other.

6. The herein described means for mounting an artificial tooth structure comprising a socket member mounted in connection with said tooth structure, a clamp band member including a tooth encircling band portion, a part adapted to be mounted in connection with said band portion to engage said socket member, means for retaining said part in said socket member, said part and socket member being fashioned to prevent lateral displacement thereof one upon the other, and an artificial tooth facing mounted in connection with said artificial tooth structure and concealing said socket and part.

7. The herein described means for mounting an artificial tooth structure comprising a socket member mounted in connection with said tooth structure, a clamp band member including a tooth encircling band portion, a part adapted to be mounted in connection with said band portion to engage said socket member, means for retaining said part in said socket member, said part and socket member being fashioned to prevent lateral displacement thereof one upon the other, an artificial tooth facing mounted in connection with said artificial tooth structure and concealing said socket and part, and means for retaining said facing in position.

8. The herein described means for mounting an artificial tooth structure, said tooth structure having a backing member provided with a dove-tailed socket and a threaded sleeve part positioned centrally of the socket, comprising a clamp band member having a tooth engaging band portion and a dove-tailed part adapted to be secured to the end of said band portion and to the end of the dove-tailed socket of said backing member.

9. The herein described means for mounting an artificial tooth structure, said tooth

structure having a backing member provided with a dove-tailed socket and a threaded sleeve part positioned centrally of the socket, comprising a clamp band member having a tooth engaging band portion and a dove-tailed part adapted to be secured to the end of said band portion and to the end of the dove-tailed socket of said back-
ing member, and a screw passed through said part and into the threaded sleeve of the 10 backing member for retaining said parts together.

In testimony that I claim the foregoing as my invention I have signed my name this 4th day of June, 1925.

LAWRENCE A. KIANDER.
